UNITED STATES PATENT OFFICE.

JAMES A. LIND, OF PROVIDENCE, RHODE ISLAND, ASSIGNOR OF ONE-THIRD TO WILLIS Q. SAMPSON AND ONE-THIRD TO FRED E. HORTON, BOTH OF CRANSTON, RHODE ISLAND.

METHOD OF FORMING NEEDLES.

1,057,860.

Specification of Letters Patent.

Patented Apr. 1, 1913.

Application filed May 22, 1911. Serial No. 628,759.

To all whom it may concern:

Be it known that I, JAMES A. LIND, a citizen of the United States, residing at the city of Providence, in the county of Providence and State of Rhode Island, have invented certain new and useful Improvements in Methods of Forming Needles, of which the following is a specification, reference being had therein to the accompanying drawing.

This invention relates to an improved method of forming an easy threading sewing machine needle, and has for its object to provide a simple and practical method whereby my improved construction of needle may be formed of one integral piece of wire by reducing the portion of the body of the wire and folding said reduced portion back upon the body portion forming a flexible arm integral with the body and leaving sufficient stock at the fold or bend to be drawn out to form the needle point, the eye is then formed in the stock near the point on the inner edge of the body, said eye having an opening covered by the folded portion. A retaining member for securing the free end of the folded portion or resilient arm is applied to the body and the shank is enlarged to the standard size by any suitable means.

With these and other objects in view, the invention consists of certain novel features of construction, as will be more fully described and particularly pointed out in the appended claims.

In the accompanying drawings: Figure 1 shows a straight piece of wire from which the needle is constructed. Fig. 2— shows the first operation which reduces the end portion of the wire. Fig. 3— shows the operation for shaping the end of the wire and flattening one side of the same. Fig. 4— is a section at 4—4 of Fig. 3. Fig. 5— is a section at 5—5 of Fig. 3. Fig. 6— is a section at 6—6 of Fig. 3. Fig. 7— shows the reduced portion of the wire bent at a of Fig. 3 and folded lengthwise back upon the body portion. Fig. 8— shows the stock drawn out at the bend to form the needle point. Fig. 9— shows the body portion of the stock grooved longitudinally to receive the thread. Fig. 10— shows the opposite side of the needle also provided with a short groove. Fig. 11— is an enlarged cross section on line 11—11 of Fig. 10 showing the relative depths of the grooves. Fig. 12—

shows the eye formed by cutting through the same between the grooves. Fig. 13— is an enlarged view showing a portion of the end of the needle and the eye formed therein. Fig. 14— shows an enlarged detail in section of the retaining sleeve. Fig. 15— is an enlarged end view of the sleeve showing the split forming flexible lips. Fig. 16— shows said sleeve in position on the shank and engaging the free end of the flexible arm to hold the same in position against the body. Fig. 17— is a perspective view of the shank enlarging plate. Fig. 18— shows the plate bent up into a U-shape in cross section ready to receive the shank of the needle. Fig. 19— shows the sheet stock wrapped and swaged around the shank. Fig. 20— is a cross section on line 20—20 of Fig. 19.

Referring to the drawings 20 designates a plain piece of wire from which the needle is formed, a portion of the body of said wire being reduced at 21 and its end 22 being preferably brought nearly to a point in the first operation. The second operation is to flatten one side of the wire as at 23 and offset the end of the reduced portion giving the same a concavo-convex shape as at 24. The next operation is to bend this reduced portion substantially at a preferably at or just above the place where the reduction of stock commences, this reduced portion being folded lengthwise back upon the body portion 20 bringing the flattened surfaces 23—23 together and forming a thin flexible arm 21. The stock at the fold or bend 24 is then drawn out and reduced to a sharp point 25. The next operation is to form a groove 26, by milling or otherwise, lengthwise of the body portion 20 in which the thread may lie while the needle is passing through the work. Another and shorter groove 27 is also formed by milling or otherwise in the opposite side of the body portion of the needle leaving a thin fin 28 between the two grooves, as illustrated in the enlarged sectional view in Fig. 11. The eye 29 of the needle is then formed through the fin 28 near the lower ends of the slot 26 and 27 by a broach, drill, bur, or other suitable means. An enlarged view of the pointed end of the needle showing the shape of this eye 29 is illustrated in Fig. 13, one side of the eye having an opening at 30 through the side of the stock, said opening being covered by the folded portion or flexible arm 23, 110

whereby a loop or bight of the thread may be readily passed down between the flexible arm and the body portion and into the eye, quickly and easily threading the same without the necessity of passing the end of the thread through said eye.

In practice it is found desirable in most cases to provide means for binding the upper or free end 31 of the flexible arm 10 to the body portion of the needle so as to positively close the eye and prevent the thread from pulling out, also to prevent the flexible arm from catching in the fabric it is passing through. To accomplish this 15 binding purpose I have provided a sleeve 32, see Fig. 14, the lower edge of which is turned slightly outward as at 33, while the upper edge is turned slightly inward as at 34, said upper edge being provided with a 20 plurality of slits or slots so that when this sleeve is applied to the needle the lower edge fits over the free end 31 of the flexible arm, while the upper edge of the sleeve grips and binds the body portion of the needle 25 frictionally holding said sleeve in any desired position on the body, either when it is pressed down over the end of the arm or when drawn up to release the arm to permit the threading of the needle.

30 In order to facilitate the forming of the needle I preferably employ a wire whose diameter is substantially that required for the body of the needle so as to minimize the drawing or reducing operation, in which 35 case the shank of the needle is naturally smaller than the standard size, thus requiring said shank to be enlarged. To accomplish this in a simple and effective manner I draw up a piece of sheet stock 35 into a 40 U-shape in cross section, as illustrated in Fig. 18, and then wrap and swage this stock around the shank portion of the needle enlarging the same to the required size, as illustrated in Figs. 19 and 20, but I do not 45 restrict myself to this method of enlarging the shank as any suitable method or means for this purpose may be employed. Neither do I restrict myself to the use of a wire whose diameter is that of the body of the 50 needle as a wire of any desired size or shape relative to the size or shape of the needle may be employed without departing from the spirit and scope of my invention.

The needle after being formed is then 55 tempered and polished in the usual way.

By my improved method of forming a needle I am enabled to fold a piece of wire lengthwise upon itself and draw out the stock at the bend into a point, the folded 60 portion forming a flexible arm the whole being formed of one piece integral with the body portion of the needle, and without the

employment of heat which would be necessary if this arm was soldered or welded into position. By this method I am enabled to produce a needle of this character in a simple, inexpensive and practical manner all the operations in which may be performed successively and automatically while the stock is cold.

I claim:

1. An improved method of forming a needle which consists in folding a wire lengthwise upon itself, drawing out the stock at the end into a point and forming an eye in the stock near the point.

2. An improved method of forming a needle which consists in folding a wire lengthwise upon itself, drawing out the stock at the bend into a point and forming an eye in the stock near the point, and enlarging the shank by attaching an extra piece of stock thereto.

3. An improved method of forming a needle which consists in flattening a wire on one side, folding the wire lengthwise upon itself bringing the flattened portions together drawing out the stock at the bend into a point and forming an eye in the stock near the point.

4. An improved method of forming a needle which consists in reducing a portion of wire, folding said reduced portion upon the body portion of the wire, drawing out the stock at the bend into a point, and forming an eye in the stock near the point.

5. An improved method of forming a needle which consists in reducing and flattening a portion of wire, folding the flattened portion upon itself bringing said flattened surfaces together, drawing out the stock at the bend into a point, and forming an eye in the stock having an opening covered by the folded portion, and enlarging the shank by attaching to the same an extra piece of stock.

6. An improved method of forming a needle which consists in reducing and flattening a portion of wire, folding the flattened portion upon itself bringing said flattened surfaces together, drawing out the stock at the bend into a point, and forming an eye in the stock having an opening covered by the folded portion, applying to the body thereof a retaining member for securing the free end of the folded portion to the body portion and enlarging the shank by wrapping and swaging around the same an extra piece of stock.

In testimony whereof I affix my signature in presence of two witnesses.

JAMES A. LIND.
